UNITED STATES PATENT OFFICE.

DANIEL W. RIDDLE, OF MAYWOOD, CALIFORNIA.

DEPTH GAUGE FOR ROAD TOOLS.

Application filed March 2, 1927. Serial No. 171,977.

This invention relates to depth gauges for road tools of the character employed in grading or otherwise working the surface of a roadway, and the invention relates more particularly to a device adapted to ride upon the curb to limit the depth that the tool penetrates the road bed.

An object of the invention is to make it possible to grade the road accurately to a fixed level. The invention is especially useful in grading roads to any predetermined level, preparatory to paving the same, in order that after constructing the pavements thereon, of the thickness required in the contracts under which the roads are being built, the finished surface of the pavement will correspond accurately to the established grade throughout the length of the pavement.

Another object of the invention is strength and simplicity of construction.

A further object is attachability of the device to a road tool of standard construction.

The accompanying drawings illustrate the invention:

Fig. 1 is a side elevation of a depth gauge constructed in accordance with the provisions of this invention, a road tool, on which the gauge is mounted, being indicated in broken lines. The curb on which the gauge rests is also indicated.

Fig. 2 is an enlarged side elevation of the invention, partly in section.

Fig. 3 is an enlarged elevation of Fig. 2, partly in section, from the line indicated by 3—3, Fig. 2.

Referring to the drawings, there is provided an angular bracket 4 of any suitable construction, provided, in this instance, at one end with a flange 5 for attaching the bracket to a road tool. Such a road tool is indicated in broken lines at A in Fig. 1. The tool thus indicated is provided with a scraper blade B. The flange 5 is attached close to the upper edge of the scraper B by bolts 6 or any other suitable fastening devices. The legs 7 of the member 4 projects upwardly from the scraper blade B and the other leg 8 of said member 4 extends substantially horizontally and is provided at one end with a split bearing 9 in which is clamped a cylindrical stem 10. The clamping effect is produced by bolts 11 which draw the opposite halves of the bearing 9 toward each other. It will thus be seen that the stem 10 is adjustably mounted in the bearing 9 so that

said stem can be raised and lowered relative to the bracket 4. Also the stem can be rotated relative to the bracket.

The stem 10 terminates at its lower end in a fork 12, which carries a roller 13 rotatably mounted in the fork by a bearing of any suitable construction, preferably an anti-friction bearing of the roller type. The bearing rollers 14 surround a bolt 15 which constitutes the shaft upon which the roller 13 turns.

It will be readily understood that when the bolts 11 are loosened the roller 13 may be raised or lowered so as to run on the upper face of a curb C when the blade B is positioned at a predetermined level relative to said face; and that the roller 13 may be turned in a horizontal plane to permit of the blade B being rotated horizontally to different angular positions with respect to the curb C.

Preferably, the shaft 15 is provided with an oil duct 16 which extends from one side of the middle portion of the shaft to one end thereof, so that lubricant may be injected into the bearing through the duct 16. Preferably, a nipple 17 is threaded into the duct 16 and communicates with said duct so as to facilitate injecting the lubricant with a grease gun.

The invention operates as follows:

Assuming, for example, that a road bed is to be graded to a given depth below the level of the upper edge of the curb, indicated at C in Fig. 1, the road tool A will be drawn into position so that the roller 13 will overhang the curb C and the operator will loosen the bolts 11 so that the roller 13 can be elevated sufficiently for this purpose. Then the operator will adjust the scraper blade 13 to the required depth. Having done this, the operator will see that the roller 13 rests upon the upper face of the curb and he will then tighten the bolts 11, thus insuring that the lower edge of the scraper blade will move at a given distance from, and parallel to, the upper face of the curb.

In paving a road, that is to be provided with curbs along its sides, the curbs are constructed first, and thus, by utilizing the fixed level established by the completed curb for regulating the level at which the scraper blade operates, there is secured a uniformity of grade that can not possibly be obtained when the curb is not utilized in this way.

I claim:

A depth gauge of the character described comprising an angular bracket provided with approximately vertical and horizontal legs, the lower end of the vertical leg provided with an attaching flange, the horizontal leg provided with a bearing positioned with its

bore extending vertically, a cylindrical stem slidably and rotatably engaging said bore, a means to releasably clamp the stem in the bearing, a fork on the lower end of the stem, and a roller rotatably mounted in said fork.

Signed at Los Angeles, Calif., this 18th day of January, 1927.

DANIEL W. RIDDLE.
